UNITED STATES PATENT OFFICE.

FRANCIS M. HENRY, OF MINNEAPOLIS, MINNESOTA.

CANAL AND THE FILLING AND EMPTYING OF THE LOCKS THEREOF.

Application filed March 18, 1926. Serial No. 95,610.

My invention relates to improvements in canals and the filling and emptying of locks thereof, and to this end, generally stated, consists of the novel devices and combinations of devices hereinafter described and defined in the claims.

In the accompanying drawings, which illustrate the invention, like characters indicate like parts throughout the several views.

Referring to the drawings:

Fig. 1 is a plan view showing one form of the invention;

Fig. 2 is a side elevation of the same;

Fig. 3 is a transverse vertical section taken on the line 3—3 of Fig. 1;

Fig. 4 is a view coresponding to Fig. 1 but showing another form of the invention;

Fig. 5 is a side elevation of the invention shown in Fig. 4;

Fig. 6 is a view principally in transverse vertical section taken on the line 6—6 of Fig. 4;

Fig. 7 is a transverse vertical section taken on the line 7—7 of Fig. 4;

Fig. 8 is a fragmentary view corresponding to Fig. 7 but showing a modification of the siphon; and

Fig. 9 is a view corresponding to Fig. 8 but showing a modification.

The numeral 15 indicates a river having a lower pool 16 and an upper pool 17, and a tail race 18 empties into the river between said pools.

Referring first to the invention as illustrated in Figs. 1, 2 and 3, the numeral 19 indicates two lower locks at the head of a lower pool 16 and two upper locks 20 at the foot of the upper pool 17. Connecting the two sets of locks 19 and 20 is an elevated artificial canal 21 of reinforced concrete construction loosely supported on columns or retainer walls 22. To keep the canal 21 out of direct contact with the columns or retaining walls 22 there is interposed therebetween joint strips 23 of copper or other suitable material. By thus supporting the canal 21 on the columns 22 the same is free to contract or expand both longitudinally and transversely under varying weather conditions.

The canal 21 extends along the river 15 at one side thereof and spans the tail race 18. In the sides of the canal 21 are a plurality of overflow openings 21^a located directly over the tail race 18 so that they discharge therein.

The upper locks 20 are filled from the upper pool 17 through conduits 24 formed in the outer walls of said locks and having a plurality of laterals 25 that open directly into said locks. Each conduit 24 has at its intake end a gate 26, and a Y-shaped conduit 27 is formed in the bottom of the canal 21 with its arms connected to the conduits 24 at their discharge end. The main body 60 of the conduit 27 extends longitudinally of the canal 21 at the center thereof and has a plurality of longitudinally spaced openings 28 arranged to discharge into the canal 21 through the bottom thereof to fill said canal. A gate 29 is installed in the receiving end of each arm of the conduit 27. Leading from the discharge ends of the conduits 24 are drain conduits 30 having gates 31 installed therein, and which conduits 70 are arranged to discharge, the one into the river 15, and the other into the tail race 18. A drain conduit 32, equipped with a gate 33, leads laterally from the main body 75 of the conduit 27 and is arranged to discharge 80 into the river 15.

Extending longitudinally of the canal 21 is a long conduit 34 for filling the locks 19 from the pool 17 or locks 20 or both. This conduit 34 is formed partly in the center wall between the locks 20, partly in the bottom of the canal, and partly outside of said canal. The upper or intake end of the conduit 34 is extended along the bottom of the pool 17 for considerable distance above the 90 locks 20 and provided with a plurality of longitudinally spaced intake openings 35. An emergency gate 36 is installed in the conduit 34 above the central wall between the locks 20 and a gate 37 is installed in said conduit just below said gate 36. A conduit 38 for each lock 20 is formed in the central wall between said locks and connected to the respective lock by laterals 39. The lower ends of the conduits 38 are arranged to discharge into the conduit 34 just below the locks 20 and each thereof is equipped below the laterals 39 with a gate 40. 100

The lower end of the conduit 34, at the upper end of the central wall between the locks 19, has two parallel branches 41 formed in said wall and arranged to discharge into the lower pool 16. Each branch conduit 41 is provided with a plurality of longitudinally spaced laterals 42 arranged to discharge 110 into the respective lock 19 for filling or emptying the same. A gate 43 is installed

in each conduit 41 above its laterals 42 and a gate 44 is installed therein below said laterals.

For filling or partly filling the locks 19 from the canal 21, there is formed in the bottom of said canal, above the locks 19, a conduit 45 that extends substantially parallel to the conduit 34 and is provided with a plurality of openings 46 that open into said canal through the bottom thereof. The discharge end of the conduit 45 is connected to the conduit 34 at the junction of the conduits 41 therewith and is equipped with a gate 47. Leading from the conduit 45, up stream from the gate 47, is a laterally extended drain conduit 45 equipped with a gate 49.

The locks 19 may also be filled from the canal 21 through conduits 50 formed in the outer walls of said lock with their upper ends opening into said canal above the locks 19, and which conduits have laterals 51 that open directly into said locks. Installed in each conduit 50, above the laterals 51, is a gate 52 and also installed in said conduit, below said laterals, is a gate 53. Leading from the gates 53 are drain conduits 54 that extend laterally outward from the outer walls of the locks 19 and are formed in the wing walls 55 of said walls and provided with a plurality of laterals 56 arranged to discharge into the lower pool 16.

Normally, all of the gates are closed with the exception of the emergency gate 36. To fill the locks 20 from the pool 17, the gates 26 are open to permit a flow of water through the conduits 24 and the laterals 25 into said locks, and to drain said locks, the gates 31 are open to permit a flow of water through the laterals 25 and drain conduits 30 into the river. To fill the canal 21 from the upper pool 17, the gates 26 and 29 are opened, or to empty the locks 20 into the canal 21, the gates 29 are opened to permit a flow of water through the laterals 25, conduits 24, conduit 27 and openings 28.

To fill the locks 19 from the upper pool 17, the gates 37 and 43 are opened to permit a flow of water through the conduit 34, conduits 41 and laterals 42. The locks 19 may also be filled by opening the gates 52 to permit a flow of water from the canal 21 through the conduits 50 and laterals 51 into said locks. The canal 21 may be also filled from the conduit 34 by opening the gate 47 to permit a flow of water from said conduit into the conduit 45 and through its discharge openings 46. To drain the locks 19, the gates 53 are opened to permit a flow of water through the laterals 51, conduits 50 and drain conduits 54 and laterals 56.

To drain the canal 21 at the close of a season, or for another purpose, the gates 49 and 33 are opened to permit a flow of water from the canal into the conduit 45 through the openings 46, and from thence through

the conduit 48, which discharges into the river 15.

From the above description, it is evident that the lower locks 19 may be filled directly from the upper pool 17 without taking any water whatsoever from the canal 21 or said locks may be filled partly or entirely from the lock 20 through conduits 38 and 34 or from the canal 21. The canal 21 may be filled either directly from the upper pool 17 through the conduits 24 and 27 or from the upper locks 20 through the same conduits, or it may be filled from the upper pool 17 through the conduits 34 and 45. By emptying the locks 19 through the laterals 54, that extend away from said locks, the lower pool 16 in front of said locks is not agitated, so that boats may closely approach said locks while the same are being emptied. Also, by filling the locks 19 directly from the upper pool 17 and emptying the locks 20 into the river and tail race 18 through the conduits 24 and 30, or through the conduits 38—34 the water in the canal 21 is not agitated, so that boats are not disturbed during their travel between the locks and while in front of the locks 20 during the emptying of the same.

Referring now to the invention as illustrated in Figs. 4 to 7, inclusive, the construction and arrangement of parts are substantially identical with those shown in Figs. 1 to 3, inclusive, and like parts have like reference characters, with the exception of parts 34, 45, 46, 47 and 48. Along the land side of the locks 19 is a reservoir 57 having a holding capacity of several times that of the locks 19. This reservoir 57 is automatically filled from the pool 17 or locks 20, or both, through a conduit 34' like the conduit 34, with the exception that it discharges into the reservoir 57 instead of the locks 19. Normally, the gates 36 and 37 are open so that the reservoir 57 is automatically filled through the conduit 34', and when the level thereof reaches the level of the pool 17, the filling action thereof is automatically stopped.

The locks 19 are filled from the reservoir 57 through a siphon 58, the discharge leg 115 of which is connected to the conduits 41 above the gates 43. This siphon 58 is formed partly in the wall between the reservoir 57 and canal 21, and partly in the bottom of said canal, and has in its crown a 120 gate 59. It will be noted, by reference to Fig. 7, that the crown of the siphon 58 is below the water level in the reservoir 57, so that when the gate 59 is open, the siphoning action is automatically started to fill the 125 locks 19 from the reservoir 57.

To fill the canal 21 from the reservoir 57, there is formed in the bottom of said canal a conduit 60 that extends from said reservoir to the center of the canal 21 and thence at 130

right angles up stream, and has formed therein a multiplicity of longitudinally spaced openings 61 that open into said canal from the bottom thereof. A gate 62 is installed in the conduit 60 at its intake end. A drain conduit 63 leads from the elbow of the conduit 60, is arranged to discharge into the river 15, and is provided with a gate 64. In the top of the lower wall of the reservoir 10 57 is an overflow 65 from said reservoir to the lower pool 16, and also formed in said wall is a drain conduit 66 equipped with a gate 67. By opening the gate 64, the canal 21 may be drained at the close of a season 15 or for any other purpose, and by opening the gate 67, the reservoir 57 may be drained.

Referring now to the invention illustrated in Fig. 8, the locks 19 are filled from the reservoir 57 through a siphon 68, the crown 20 of which is above the water level in said reservoir. To start a siphoning action in the siphon 68, there is provided an upstanding pipe 69 at the crown of said siphon, to which may be applied a connection for exhausting 25 the air in said siphon or through which water may be pumped to fill the siphon.

Referring now to the invention as shown in Fig. 9, the locks 19 are filled from the reservoir 57 through a conduit 70 that leads 30 from the bottom of said reservoir and is connected to the conduits 41 above the gates 43.

The lower lock gates 81 in both the lower and upper locks 19 and 20 are provided, as 35 shown, with valves 82 through which the locks may be emptied.

What I claim is:

1. The combination with upper and lower locks, of a canal section between said locks, 40 and gate-controlled water-conveying means for filling and emptying the locks without disturbing the water in the canal section.

2. The combination with upper and lower locks, of a canal section between said locks, 45 and selective gate-controlled water-conveying means for filling the lower lock from a point above the upper lock, from the upper lock, or from both, without disturbing the water in the canal section.

50 3. The combination with a canal, of a lock in the canal, and gate-controlled water-conveying means having a multiplicity of longitudinally spaced intake openings for filling the lock from a point distant from the upper end of the lock.

4. The combination with a canal, of a lock in the canal, and gate-controlled means having a multiplicity of longitudinally spaced intake openings for filling the lock, 55 and a gate-controlled conduit for emptying the lock at a point distant from the lower end of the lock.

5. The combination with a canal, of upper and lower locks in said canal, a water supply conduit for the lower lock leading from the 60

canal above the upper lock, and means for controlling the flow of water through said conduit.

6. The combination with a canal, of upper and lower locks in said canal, a water supply 70 conduit for the lower lock leading from the canal above the upper lock, a gate for said conduit, a second conduit leading from the upper lock to the first noted conduit, and a gate for said second conduit. 75

7. The structure defined in claim 6 in which said second conduit empties into the first noted conduit below the gate thereof.

8. The structure defined in claim 5 in which said conduit is extended longitudinally above the upper lock and provided with a plurality of longitudinally spaced filling 80 openings.

9. The combination with a canal, of a lock 85 in the canal, a water conduit leading from the canal above the lock, upper and lower gates in the conduit, said conduit being open to the lock between said two gates, a waste pipe leading from the conduit below the lower gate and arranged to discharge outside of the canal, and a gate for the waste pipe. 90

10. The combination with a canal, of a lock 95 in the canal, a water conduit leading from the canal above the lock, upper and lower gates in the conduit, said conduit being open to the lock between said two gates, said conduit having an extension below the lower gate, extending below the lock and provided with a plurality of longitudinally spaced 100 openings located at distant points from the lock.

11. The combination with a canal, of a lock 105 in the canal, a water conduit leading from the canal above the lock to a point below the same, upper and lower gates in the conduit, said conduit being open to the lock between said two gates, a waste pipe leading from the conduit below the lower gate and extending laterally away from the lock and having a plurality of longitudinally spaced 110 openings arranged to discharge into the canal at distant points below the lock, and a gate for the waste pipe. 110

12. The combination with a canal, of a lock 115 in the canal, a water conduit for filling the lock, extending longitudinally of the canal above said lock and having a plurality of longitudinally spaced intake openings, a gate for opening and closing said conduit to the lock, and a gate-equipped drain conduit leading from said conduit above its gate. 120

13. The combination with a canal, of upper and lower locks in the canal, a reservoir, a water conduit leading from the canal above the upper lock for automatically filling the reservoir to maintain a level corresponding to the water level above the upper lock, and means for filling the lower lock 125 from the reservoir. 130

14. The structure defined in claim 13 in further combination with a second conduit leading from the upper lock to the first noted conduit, and a gate in said second conduit.
- 5 15. The combination with a canal, of a lock in the canal, a reservoir, a siphon leading from the reservoir to the lock, means for filling the reservoir to start a siphoning action to fill the lock from the reservoir, and
- 10 16. The structure defined in claim 15 in which the gate is located at the crown of the siphon.
- 15 17. The combination with a canal, upper and lower locks in the canal, a reservoir independent of the canal and locks, a water

conduit leading from the canal above the upper lock to the reservoir, and means for filling the lower lock from the reservoir.

18. The combination with a canal, of 20 upper and lower locks in the canal, a reservoir, a water conduit leading from the upper lock for filling the reservoir, and means for filling the lower lock from the reservoir.

19. The structure defined in claim 17 in 25 further combination with a gate for the conduit above the upper lock, a gate-equipped second conduit leading from the upper lock to the conduit.

In testimony whereof I affix my signature.

FRANCIS M. HENRY.
